W. PAPE.

GOVERNING MECHANISM FOR MIXED PRESSURE TURBINES.

APPLICATION FILED DEC. 27, 1911.

1,064,762.

Patented June 17, 1913.

UNITED STATES PATENT OFFICE.

WILHELM PAPE, OF CHARLOTTENBURG, GERMANY, ASSIGNOR TO GENERAL ELECTRIC COMPANY, A CORPORATION OF NEW YORK.

GOVERNING MECHANISM FOR MIXED-PRESSURE TURBINES.

1,064,762.

Specification of Letters Patent. Patented June 17, 1913.

Application filed December 27, 1911. Serial No. 668,129.

To all whom it may concern:

Be it known that I, WILHELM PAPE, a subject of the King of Prussia, residing at Charlottenburg, Germany, have invented 5 certain new and useful Improvements in Governing Mechanism for Mixed-Pressure Turbines, of which the following is a specification.

In a mixed pressure turbine installation 10 where no current is available for starting the motors that drive the condenser pumps, it becomes necessary to start the turbine with high pressure steam and permit it to exhaust freely; in other words, to operate 15 it non-condensing. When such a turbine is operated in this manner, a pressure is produced in advance of the low-pressure part 20 of the turbine which is above that of the atmosphere. Consequently steam from this stage will pass through the low pressure 25 throttle valve into the accumulator and the pressure regulator, the latter modifying the action of the speed governor on the valve mechanism. The movable part of the pressure 30 regulator will therefore be carried to its highest position and held fast, so that the low-pressure valve will constantly remain open. This opening of the low pressure 35 valve causes the high-pressure valve to close, assuming a connection between them, so that high pressure operation under 40 these conditions becomes impossible. In order to obviate this difficulty I have devised a mechanism which permits of the pressure regulator being held fast in its 45 lowest position, so that the low-pressure valve will remain completely closed while the turbine is started with live or high pressure steam.

40 In the accompanying drawing is shown one of the embodiments of my invention wherein—

Figure 1 is an end view of a mixed pressure turbine; Fig. 2 is a diagrammatic illustration of the governing mechanism therefor; Fig. 3 is a sectional view of the low pressure valve actuating motor and its pilot valve; and Fig. 4 is a detail of a valve.

1 indicates a mixed pressure turbine having a low pressure admission valve 2 and a high pressure admission valve 3. The low pressure steam is received from an accumulator 4 that is connected by the pipe

5 with the exhaust of a reciprocating or other engine. High pressure steam is admitted to the turbine from a boiler by the pipe 6. The exhaust from the turbine enters the condenser 7.

The low pressure valve or valve means is actuated by a motor comprising a piston 8 and a cylinder 9 controlled by the pilot valve 10. The pilot valve is surrounded by a ported sleeve 11 that is actuated by a means to be described later. The sleeve has ports that register with ports leading to the motor. 65 The high pressure valve or valve means is also actuated by a motor comprising the cylinder 12, a piston 13 and a pilot valve 14 of usual construction.

15 indicates a speed governor that is 70 driven by the shaft 16 which may be the main shaft of the turbine or a secondary shaft. It is provided with a sliding collar 17 which is connected to the weights and also to a lever 18 pivoted at 19 to a fixed support. The left hand side of the governor collar is pivotally attached to the lever 18^a, the latter being pivotally connected to the piston rod 20. The right hand end of the lever 18 is connected by a link 21 to a secondary governor lever 22. The lever 22 is pivotally attached to and operates the pilot valve 14 and is also attached to the rod 23. Pivotally connected to the piston rods 20 and 24 is a lever 25 that is also pivotally attached to the rod 23 and actuates the pilot valve 14 under certain conditions. 85

26 indicates a pressure regulator comprising a cylinder 27 and a piston and its rod 28, the latter being connected to the lever 90 29. Fluid under pressure is admitted by the pipe 30 from the accumulator 4. Acting in opposition to the pressure is a coiled compression spring 31. The left hand end of the lever 29 is connected to the sleeve 11 of 95 the pilot valve, said sleeve coöperating with the pilot valve to regulate the admission of fluid to the motor, and being adjusted as to its position in response to pressure changes in the accumulator. At the lower end of the 100 ported sleeve is a dash pot comprising a piston 32 and a cylinder 33. Carried by the piston are valves 34 that open freely as the piston moves downward and close as it moves upward to retard its action. As 105 shown in Fig. 4, these valves are provided

with a light spring to insure seating. A regulator responsive to condenser pressure is also provided comprising a casing 35, piston 36 and a compression spring 37. Fluid under pressure is admitted to the cylinder from the condenser 7 by the pipe 38. Said pipe may be connected to the exhaust end of the turbine. The piston rod 39 of this regulator is pivotally attached to the lever 29 and forms an adjustable fulcrum therefor which is responsive to pressure changes within the condenser. As the pressure changes the fulcrum is raised or lowered. It will therefore be seen that the low pressure valve means is acted upon by a speed governor, by a regulator responsive to changes in accumulator pressure, and by a regulator responsive to condenser pressure. If the pressure within the condenser rises, as it would if the pumps were not working, the fulcrum of the lever 29 is moved upwardly thereby depressing the ported sleeve 11 which opens the ports leading from the pilot valve to the motor in a manner to cause the low pressure valve means to close. The turbine will now operate with high pressure steam because the regulator responsive to accumulator pressure is prevented from acting. Disturbance to the operation is therefore avoided since it is possible, even with a rather poor vacuum to maintain the full load duty on the turbine even when the supply of low pressure steam is no longer sufficient to carry the load.

35 For normal operation the speed governor moves the pilot valves in their proper sequence as the load changes thereby causing the turbine to receive and be driven by low pressure steam so long as the supply is sufficient, to receive a mixture of low and high pressure steam and finally to receive high pressure steam only. This control of the valves by the governor is modified by the action of the regulator that is responsive to the pressure of the source of low pressure supply, *i. e.* the steam in the accumulator 4. Moving the sleeve 11 has the effect of giving a greater opening to the motor ports than is given by the action of the speed governor. The low and high pressure valves 2 and 3 are connected together in the sense that the closing of the valve 2 in response to the action of the pressure regulator 26 causes the valve 3 to open due to the arrangement of the lever 25, rod 23 and lever 22. This last mentioned feature is not claimed herein because it forms the subject matter of a patent of mine No. 1,029,311 of June 11, 1912.

60 In accordance with the provisions of the patent statutes, I have described the principle of operation of my invention, together with the apparatus which I now consider to represent the best embodiment thereof; but I desire to have it understood that the

apparatus shown is only illustrative, and that the invention can be carried out by other means.

What I claim as new and desire to secure by Letters Patent of the United States, is:—

1. In combination, a mixed pressure turbine, conduits admitting low and high pressure motive fluid thereto, valve means controlling the passage of fluid therethrough, a governor controlling the action of both valve means, a pressure regulator that modifies the action of the governor on said means, and a second pressure governor that under certain conditions modifies the action of the first.

2. In combination, a mixed pressure turbine, conduits admitting low and high pressure motive fluid thereto, valve means controlling the passage of fluid therethrough, a condenser receiving the exhaust of the turbine, a governor controlling the valve means, a regulator responsive to the pressure of the low pressure source, and a second regulator responsive to exhaust pressure, both of said regulators modifying the action of the governor on said valve means.

3. In combination, a mixed pressure turbine, conduits admitting low and high pressure motive fluid thereto, valve means controlling the passage of fluid therethrough, a speed governor driven by the turbine for controlling the valve means, a regulator responsive to the pressure of fluid supplied to the turbine, and a second regulator responsive to the exhaust pressure of the turbine, both of said regulators modifying the action of the speed governor.

4. In combination, a mixed pressure turbine, conduits admitting low and high pressure motive fluid thereto, valve means controlling the passage of fluid therethrough, the valve means for the low pressure source tending to open when high pressure fluid is admitted for the purpose of starting, and a regulator that overcomes said tendency and temporarily holds said valve means closed.

5. In combination, a mixed pressure turbine, conduits admitting low and high pressure motive fluid thereto, valve means controlling the passage of fluid therethrough, a governor controlling both of said valve means, a motor for actuating the low pressure valve means, a controller for the motor comprising two principal parts, one of said parts being actuated by the governor, means responsive to pressure for actuating the second part, and a regulator that under certain conditions assumes control of the second part to the exclusion of the said means.

6. In combination, a mixed pressure turbine, conduits admitting low and high pressure fluid thereto, valve means in the conduits, a governor common to both means, a motor for actuating the low pressure valve

means, a controller for the motor comprising two principal parts, a regulator responsive to the pressure of one of the sources for actuating one part of the controller, and 5 a second regulator responsive to the exhaust pressure of the turbine for actuating the other part of the controller.

7. In combination, a mixed pressure turbine, conduits admitting low and high pressure fluid thereto, valve means in the conduits, means responsive to speed changes of 10 the turbine for controlling the valve means,

a pressure regulator for modifying the action of one of said valve means under certain conditions, and a second pressure regulator that temporarily nullifies the effective action of the first. 15

In witness whereof, I have hereunto set my hand this fifth day of Decbr., 1911.

WILHELM PAPE.
